UNITED STATES PATENT OFFICE.

ELLEN DE LONG, OF CHICAGO, ILLINOIS.

GARMENT-SUPPORTER.

1,242,780.

Specification of Letters Patent.

Patented Oct. 9, 1917.

Application filed November 4, 1913. Serial No. 799,088.

To all whom it may concern:

Be it known that I, ELLEN DE LONG, a citizen of the United States, residing at Chicago, in the county of Cook and State 5 of Illinois, have invented certain new and useful Improvements in Garment-Supporters, of which the following is a description.

My invention relates to means for engaging a garment near its edge to connect the 10 same to a girdle or some other portion of the clothing to support the garment in position and especially to the clasp or fastening for engaging the garment.

The object of my invention is to provide a 15 simple, convenient, reliable and comfortable device of the kind described, adapted to secure a positive grip upon the garment without cutting or injuring the fabric and of such form that its use will cause no inconvenience or discomfort to the wearer.

To this end my invention consists in the 20 novel construction, arrangement and combination of parts herein shown and described, and more particularly pointed out 25 in the claims.

In the accompanying drawings wherein like or similar reference characters indicate like or corresponding parts:

Figure 1 is an elevation of my device 30 showing the same in service.

Fig. 2 is an enlarged front elevation of my device showing the clasp open and the parts sufficiently separated to clearly show the construction.

Fig. 3 is a rear view of my device showing the clasp closed or in locked position.

Fig. 4 is an enlarged section taken substantially on line 4—4 of Fig. 3.

In the drawings for the purpose of illustration I have shown my improvement as a 40 hose supporter in which the clasp for engaging the hose consists of a member 1 formed of any suitable material having a lever 2 pivotally attached to its upper end.

The lower end of the member 1 is preferably 45 semi-circular in form with a part 3 bent up at the front to form a semi-cylindrical pocket at the lower margin of the clasp. A resilient part 4 is pivotally attached to the 50 free end of the lever 2 adapted to coöperate with the walls at the lower end of the member 1 to engage a garment. In the preferred construction the part 4 is formed of a suitable resilient wire having its extremities 55 bent or otherwise suitably formed to engage the sockets or eyes 5—5 upon the lever 2.

The central portion of the wire is formed to accurately fit within the pocket at the lower end of the member 1 and with portions 6—6 at each side of the supporter adapted to 60 serve as springs and permit a slight resiliency between the curved portion 4 and the end of the lever 2 to accommodate garments of different thicknesses. The pivotal connection 7 between the lever 2 and member 1 65 is so positioned that when the member 4 is positioned in the pocket 8 and the free end of the lever 2 forced down to force the member 4 into the pocket, the eyes 5 will pass slightly beyond or to the side adjacent the 70 member 1 of the line extending from the central line of the pivotal connection 7 and the free end of the part 4 in engaging position thus positively locking the part 4 in position. 75

In the preferred construction an extension 10 is provided upon the lever 2 to serve as a handle for conveniently manipulating the same and an aperture 11 is provided in the body portion of the member 1 to reduce 80 the weight of the same and provide ventilation and also to afford convenient access to the back side of the handle 10 for unlocking and disengaging the clasp. In the preferred construction a plurality of slits 12—12 are 85 provided near the margin of the member 1 adapted to receive a suitable band or ribbon 14 to serve as a backing for the clasp and prevent the metal of the clasp coming into contact with the body of the wearer. 90 A transverse bar 15 is also provided upon the member 1 adjacent the hinge 7 for attaching a band or strip 16 to the clasp to support the same in position and in the preferred form the ends of the ribbon 14 are positioned adjacent the bar 15 and inclosed in 95 the loop of the band 16 thus forming a smooth, neat finish to this portion of my device.

Any suitable means may be provided for 100 supporting my device in position. As shown a metal loop 17 is provided at the upper end of the band 16 and a connector 18 engages the loop at one end and its opposite end is permanently secured to the lower portion of 105 a girdle 19 or other convenient garment. In the preferred construction the connector 18 is substantially triangular in form with the base of the triangle secured to the girdle and is apex to the clasp. The triangular connector is preferably formed of any desired 110 number of elastic strips sewed or otherwise

attached to the lower portion of the girdle at the desired intervals and converge toward the clasp. The object of this arrangement is to insure a substantially uniform downward pull upon the girdle and to accurately position the clasp upon the hose when in service, thus avoiding discomfort due to the unequal strains otherwise, upon the girdle and upon the hose.

10 Having thus described my improvement it is obvious that various immaterial modifications may be made in my device without departing from the spirit of my invention, hence I do not wish to be understood as 15 limiting myself to the exact form of construction shown.

What I claim as new and desire to secure by Letters Patent is:

1. A garment supporter comprising a 20 member having a semi-circular part at one end and with the margin of said curved part bent over to form a semi-cylindrical channel, means attached near the opposite end of said member for supporting the same, a 25 resilient part adapted to enter said channel and coöperate with the semi-circular walls thereof to engage a garment, and means pivotally connecting said member and part adapted to control their relative position.

30 2. A garment supporter comprising a member having a semi-circular part at one end and with the margin of said curved part bent over to form a semi-cylindrical channel, means attached near the opposite end of 35 said member for supporting the same, a part formed of resilient wire adapted to enter said channel and coöperate with the semi-circular walls thereof to engage a garment, and means pivotally connecting said member and part adapted to control their relative position.

40 3. A garment supporter comprising a member having a semi-circular part at one end and with the margin of said curved part 45 bent over to form a semi-cylindrical, semi-

circular channel, means attached near the opposite end of said member for supporting the same, a resilient part adapted to enter said channel and coöperate with the semi-circular walls thereof to engage a garment, 50 and rigid means connecting said member and part adapted to control their relative position.

4. A garment supporter comprising a 55 member having a semi-circular part at one end and with the margin of said curved part bent over to form a semi-cylindrical channel, means attached near the opposite end of said member for supporting the same, a resilient part adapted to enter said channel and coöperate with the semi-circular walls thereof to engage a garment and means rigidly connecting said member and part and pivotally attached to each adapted 60 to control their relative position.

5. A garment supporter comprising a 65 member having a semi-circular part at one end provided with a central opening and with the margin of said curved part bent over to form a semi-cylindrical channel, 70 means attached near the opposite end of said member for supporting the same, a part formed of resilient wire adapted to enter said channel and coöperate with the walls thereof to engage a garment and a 75 rigid lever pivotally connecting said member and part adapted to control their relative position, the free end of said lever extending over said central opening in the member when said supporter is in an engaging position whereby said lever may be manually 80 operated to release said supporter through said opening.

In testimony whereof, I have hereunto signed my name in the presence of two subscribing witnesses.

ELLEN DE LONG.
